UNITED STATES PATENT OFFICE.

FRANZ PAMPE, OF HALLE-ON-THE-SAALE, GERMANY; ELEONORE JOSEFINE JOHANNA PAMPE, WIDOW, ONE-FOURTH INTEREST, PHIL-BRUNO OTTO ALEXANDER PAMPE, SON, THREE-EIGHTHS INTEREST, AND OTTO ALFRED ROBERT PAMPE, SON, THREE-EIGHTHS INTEREST OF THE ESTATE OF SAID FRANZ PAMPE, DECEASED.

PROCESS FOR SEPARATING THE FIRST AND LAST RUNNINGS IN DISTILLATION AND RECTIFICATION.

1,145,332.

Specification of Letters Patent.

Patented July 6, 1915.

Application filed April 18, 1905, Serial No. 256,277. Renewed May 28, 1915. Serial No. 31,088.

To all whom it may concern:

Be it known that I, FRANZ PAMPE, a subject of the King of Prussia, German Emperor, residing at the city of Halle-on-the-
5 Saale, in the Kingdom of Prussia, German Empire, have invented certain new and useful Improvements in Processes for Separating the First and Last Runnings in Distillation and Rectification; and I do hereby de-
10clare the following to be a full, clear, and exact description of the invention, such as will enable others skilled in the art to which it appertains to make and use the same, reference being had to the accompanying drawings,
15 and to letters or figures of reference marked thereon, which form a part of this specification.

My invention has reference to a process for the distillation and rectification of alcohol, its subject matter consisting of a process for the elimination of the fusel oils during said distillation and rectification.

During the distillation and rectification of alcohol the fusel oils are present in the 25 distilling and rectifying column respectively in an undissolved condition, in the lower portion thereof where there is a mixture of alcohol and water having so low a percentage of the former that it is incapable of dis-
30 solving the fusel oils. When subjected to heat the fusel oils in this part of the column are, consequently, almost entirely evaporated and ascend in the form of vapor into the parts of the column lying immediately
35 above. In conjunction with these fusel oil vapors those of the evaporated alcohol also ascend at the same time into the upper portions of the column; here the percentage of alcohol in the ascending vapors gradually
40 increases so that, at a predetermined point, the fusel oils are dissolved by the stronger alcohol. After the fusel oils have been dissolved by the alcohol, it becomes still more difficult to eliminate and remove them from
45 the column; the molecules of the alcohol exert a certain attraction upon those of the fusel oil. In addition to this the fusel oils,

after their final solution in alcohol, form solutions from which the fusel oils can no longer be evaporated away. In view of this, 50 separating means should be provided at a point in the distilling or rectifying column, between the lowest portion and that higher portion thereof where the fusel oils pass from the undissolved to the dissolved state, 55 a point at which there is a dividing layer where the fusel oils are not yet dissolved, but are on the very verge of being dissolved. In this dividing layer a most favorable opportunity is afforded for withdrawing the 60 fusel oils from the column. Undoubtedly the fusel oils are also in an undissolved state in the lower portions of the column, but it is not an easy matter to remove them at that point, because the fusel oil vapors tend to as- 65 cend rapidly into the upper portions of the column. If, however, certain small quantities of fusel oils should become separated from the alcohol in those parts of the column lying above the dividing layer, and there become vaporized, still they would in most cases become incorporated with the liquid (a mixture of alcohol and water) flowing downward in the column; this stream would carry them along with it and 70 so conduct them to the dividing layer. The dividing layer lies in the distilling column between its fifth to tenth floor counting from the bottom upward, provided the distilling column be about 9 meters high, possesses 75 about 40 floors and if said floors are at a distance of 0.2—0.3 meters from each other.

Now, the novel feature of my invention is to be found in the essential characteristic that steam is admitted at one side of 85 the dividing layer, in the distilling or rectifying column, and is allowed to escape at the other carrying the fusel oils with it.

My invention consists in the process whereby the fusel oils, during the distilla- 90 tion and rectification, are removed from the column by means of steam that is admitted into the column a little below the point at which the fusel oils pass from the undis-

solved into the dissolved state (*i. e.* at the dividing layer); the said steam being withdrawn from the column, at a point lying opposite that at which it was introduced, 5 together with the undissolved fusel oil vapors that have collected there. On passing the steam through the column it absorbs only very little alcoholic vapor, whereas almost the whole of the fusel oils are carried away with it.

Methods are already known for the removal of fusel oils, whereby water or steam is passed into the alcoholic liquid. In the case of these processes warm water or steam 10 is introduced into the column, at that point thereof where the fusel oils collect in a liquid form, in such large quantities that consequently a much lower percentage of alcohol is contained not only in the liquid 15 in the column, but also in the vapors thrown off thereby. Due to this lower percentage of alcohol, however, the solubility of the fusel oils in the mixture of alcohol and water is greatly inferior; the fusel oils separate 20 consequently from the water with greater ease, and they therefore rise in a liquid form to the surface of the liquid which is drawn off laterally through a union. Still the liquid left behind is saturated 25 with fusel oils, and only the superfluous portion can be eliminated. Hence the vapors coming from below and rising upward from the bottom of the column, and which also traverse the liquid, will likewise 30 not be free from fusel oils.

By the process already known the mixture of alcohol and water is diluted with water, and the fusel oils separated therefrom due to the dilution, and which float on 35 the surface of the liquid, are withdrawn in liquid form from the column together with the superficial portion of the liquid. By my process the fusel oils are carried out of the column in vapor form together with the 40 steam which is driven through the column, the arrangement being such that the molecules of fusel oil become incorporated with the particles of steam and quit the column in conjunction therewith. In order to avoid 45 as far as possible any absorption of alcohol vapors by the steam, while this latter is being conducted through the column, it is preferable to allow the steam to pass through the column as quickly as possible. 50 After the fusel oils have been removed from the column together with the steam, they are then liquefied. To effect this the steam combined with the fusel oils is conducted straight from the column, as it passes there- 55 from, into an apparatus wherein it is turned to account for heating the said apparatus. The vapors yield up their heat, and the fusel oils are consequently concentrated. The best means of effecting this is to use 60 an auxiliary evaporator or so-called "after

evaporator" for first runnings; in this the first runnings are caused to meet the said vapors and thus receive heat from the latter. As the steam, which has been removed from the column, has only carried very little alcoholic vapor along with it in its passage through the column, it has so low a percentage of alcohol that the fusel oils contained in the mixture remain totally unaffected and separate in the liquid form.

Steam is best introduced into the column at the locality of the so-called dividing layer in two ways: first, below the surface of the liquid collected on the bottom of the tray in that locality of the still, whereby the supernatant layer of fusel oils may be vaporized into the space above the tray; and second, by introducing the steam into the space above the liquid in such a manner as to give the vapors a substantially horizontal whirling motion. A suitable perforated withdrawal pipe arranged in the path of the whirling layer or zone of mixed steam and fusel oil vapors, serves as means for withdrawing such mixed vapors and discharging them to some convenient point outside the column. Steam may be introduced at a temperature of about 100° C., and should equal in quantity about 10 per cent. of that required for the whole distilling processes.

In order to render the invention clearly comprehensible, reference is made by way of example to the accompanying drawing, showing an apparatus for carrying out the invention in a suitable manner.

In this illustration, Figure 1 is a fragmentary vertical section of a portion of a column arranged as a sort of trap; Fig. 2 is a fragmentary vertical section of a distilling column, taken in the vicinity of the dividing layer; and Fig. 3 is a horizontal section of Fig. 2 in the vicinity of pipes 3 and 4.

Referring to the drawings, 1 represents a compartment of the distilling column. This column may comprise any suitable number of compartments superposed and in communication with each other. The particular compartment here illustrated is that located substantially at the so-called dividing layer where the fusel oils still remain undissolved, and just below the locality in the column where the alcoholic vapors become strong enough to dissolve the fusel oils. In practice, this compartment may be the fifth compartment from the bottom, assuming the still to be of the dimensions and to have the number of floors hereinbefore mentioned.

Near the bottom of the lower tray in compartment 1 is arranged circular perforated steam pipe 2 supplied with steam from any suitable source. This pipe is arranged to be immersed in the layer of liquid collected on the tray. Near the top of compartment 130

1 and above the liquid level therein is arranged radial steam pipe 3 having nozzles through which steam may be discharged horizontally into the vapor space of chamber 1 and tangentially to the walls thereof. Suitably spaced from steam pipe 3 and at about the same level is arranged perforated pipe 4 which projects radially into the vapor chamber. Pipe 4 is provided to withdraw 10 from the vapor chamber mixed vapors of steam and fusel oils.

The method of using the described apparatus in carrying out the process of the present invention is substantially as follows. Steam being admitted beneath the level of the liquid in the bottom of the compartment to perforated pipe 2, mixed vapors of steam and fusel oils fill the vapor space, and are caused to assume a whirling 20 movement in a substantially horizontal plane by the introduction of steam through the nozzles in pipe 3. Through perforated pipe 4 the mixed vapors are continuously withdrawn, the whirling movement given by 25 the tangentially directed jets of steam to the layer of mixed vapors serving to constantly present new quantities of the mixed vapors to the withdrawal pipe.

In Fig. 1 is illustrated a kind of trap for 30 preventing return of the fusel oils from the base of the distilling column to the still immediately therebelow. This trap is located at a level below that portion of the still shown in Fig. 2, and is advantageously employed with the means hereinbefore described in carrying out the present process. 35 37 is a wide cylindrical tube open at both ends and having its upper and lower edges slotted or serrated as shown to favor the passage of liquid along the walls of the conduit without interfering with the upward passage of vapors from the still. Surrounding 40 37 and spaced away therefrom is a cylindrical baffle 38 which projects above the edges 45 of 37 and extends downwardly toward the bottom of the compartment, stopping short thereof however. 39 is a pipe through which return condensed liquids from the upper part of the apparatus and 40 is a cup-shaped 50 member receiving the open end of said pipe. 41 is a circular perforated pipe for supplying steam. Liquid flowing into the compartment from pipe 39 fills the compartment to about the level of the upper edge of member 37. The strength of this alcoholic liquor is such that fusel oils contained therein are 55 not dissolved but accumulate as a supernatant liquid layer on the surface of the liquid

in the compartment. This supernatant layer is prevented by baffle 38 from access 60 to the space between 37 and 38. The heavier alcoholic liquid however flows under the edge of 38 and over the upper edge of 37 and thence downwardly into the still. Steam being introduced through perforated pipe 65 41, mixed vapors of steam and fusel oil, containing of course some alcohol, fill the space above the liquid and pass upwardly through the compartments of the column, ultimately arriving at compartment 1, 70 where the withdrawal of mixed vapors and steam and fusel oils is effected as described.

The apparatus described and shown and advantageously used in performing the described process forms the subject matter of 75 my co-pending application Serial No. 273,292, filed August 8, 1905.

Having now described my invention and explained the manner in which it is to be performed, I declare that what I claim as 80 my invention and desire to secure by Letters Patent is as follows:

1. A process for the removal of the fusel oils, during the distillation and rectification of alcohol, from the mixture of water, alcohol and fusel oil present in the distilling and rectifying column, consisting in introducing steam into the column, at the point where the fusel oils begin to dissolve slightly in the alcoholic mixture but nevertheless substantially the whole of such oils still remain undissolved, and withdrawing the steam mixed with fusel oil vapors from the column at another point situated at a certain distance away. 95

2. The process of separating the first and last runnings during the distillation and rectification of alcoholic liquids, which comprises carrying on such distillation and rectification in a suitable column apparatus, 100 introducing steam into such column near the locality where the fusel oils are about to dissolve, but still remain substantially undissolved, maintaining a whirling layer of mixed vapors of fusel oils and steam in such 105 locality, withdrawing such mixed vapors from the whirling layer and discharging the same outside of the column.

In testimony that I claim the foregoing as my invention, I have signed my name in 110 presence of two subscribing witnesses.

FRANZ PAMPE.
